United States Patent Office

Des. 193,799
Patented Oct. 9, 1962

193,799

BRACELET OR SIMILAR ARTICLE

Laura V. Bourne, 20 W. 87th St., New York, N.Y.

Filed Jan. 26, 1961, Ser. No. 63,706

Term of patent 14 years

(Cl. D45—4)

FIG. 1

FIG. 3

FIG. 1 is a perspective view of a bracelet or similar article showing my new design, with the magnifier thereof in normal position;

FIG. 2 is a view similar to FIG. 1 but with the magnifier in open or operative position; and

FIG. 3 is an end elevational view of the bracelet as shown in FIG. 1.

I claim:

The ornamental design for a bracelet or similar article, substantially as shown.
